UNITED STATES PATENT OFFICE.

LEWIS H. FALLEY, OF KANSAS CITY, MISSOURI, ASSIGNOR TO M. H. FALLEY, OF KANSAS CITY, MISSOURI.

METHOD OF FORMING SHEET METAL.

Application filed July 17, 1922. Serial No. 575,693.

To all whom it may concern:

Be it known that I, LEWIS H. FALLEY, a citizen of the United States, residing at Kansas City, in the county of Jackson and State of Missouri, have invented a certain new and useful Improvement in Methods of Forming Sheet Metal, of which the following is a complete specification.

The present invention relates to sheet or plate metal working, and aims to devise a novel method of producing an article from such material having a plurality of curved or twisted baffle fingers or blades of a type adapted for use as retarding or deflecting elements in connection with the control or modification of fluid currents.

Accordingly, I have devised a method which consists primarily in the cutting of a metal sheet or plate in such manner as to provide a plurality of blades or fingers adapted to be twisted in the required manner for forming the series of deflecting elements, which cutting operation also results in the formation of suitable clearance spaces between the blades or fingers for facilitating the operation of imparting the desired shape to the fingers or blades.

With this general object in view, the invention will now be described by reference to the accompanying drawing illustrating one mode of practicing the improved process, after which those features deemed to be novel will be particularly set forth and claimed.

35 In the drawing—

Figure 1 is a plan view of a sheet of metal illustrating the manner in which the same is cut or punched prior to the shaping of the baffle blades or fingers;

40 Figure 2 is a similar view showing the baffle blades or fingers after the same have been subjected to the shaping or twisting process;

Figure 3 is an end view of the same looking to the right in Figure 2; and

45 Figure 4 is a plan view similar to Figure 1 illustrating a different form of enlargements at the inner ends of the ends of the slots between the baffle blades or fingers, and also a slightly modified arrangement of said blades or fingers.

Referring now to the drawing in detail, this shows a fragment 5 of plate or sheet material in which has been produced, by 50 suitable cutting, stamping or punching op-

eration, a plurality of slits or slots 6 extending from one edge of the sheet and terminating at their inner ends in expanded portions or enlargements 7 of any desired outline, the result being that a plurality of 60 blades, fingers or baffle elements 8 are thus formed between the several pairs of adjoining slots 6. Preferably in case of the material forming the sheet being of any appreciable thickness, the slots 6 are produced 65 by cutting out narrow strips of the material along the lines of the slots, so as to facilitate clearance of the fingers 8 when subjected to the twisting process as indicated in Figures 2 and 3. The drawing shows two parallel 70 rows of the fingers 8 produced by means of cutting two sets of slots 6 extending from two opposite sides of the sheet 5, and the corners of the sheet removed by the same cutting operation, leaving end projections or 75 supporting stems 10 adapted to be employed in the mounting of the baffle structure in its position of use. In this connection it may be stated that the invention relates to the production of baffle structures of the nature set 80 forth in my copending application Serial Number 562,142, filed May 19, 1922, adapted especially for the control or modification of water currents, as will be found more fully explained in said application. 85

Any appropriate means, manual or otherwise, may be employed for the twisting of the baffle blades or fingers 8, and said blades or fingers twisted in either direction or at any angle, and bent in either direction laterally from the central or body portion of the plate or sheet 5 to any required extent according to the conditions of use for which the particular device is to be adapted, either as a current baffling, deflecting or retarding 95 appliance. The drawing shows these blades or fingers both bent in opposite directions and also twisted in opposite directions at the opposite sides of the device, but this arrangement and design may of course vary 100 within wide limits. The said twisting and bending operation is carried out far more accurately and efficiently than would otherwise be possible by virtue of the openings or recesses 7 forming the enlarged inner ends 105 of the slits or slots 6, which obviously allow each of the blades or fingers 8 to be twisted more readily and freely, and to a much greater extent than would be permitted if said recesses were not present, and all with- 110

out any distortion of the remainder of the metal. The cutting away of some of the metal along the lines of the slots 6 also facilitates the separate twisting of the fingers 8, since the adjacent edges of each pair of fingers or blades are thus permitted to clear each other without difficulty.

The shape or outline of the recesses 7 is of course immaterial, as these recesses or enlargements may be circular, as shown in Figures 1 and 2, or triangular or rectangular as indicated at 7' and 7'', respectively, in Figure 4, illustrating a construction similar to that above described with the exception that the slots 6 at the opposite sides of the plate or sheet 5' are cut parallel, thus producing blades or fingers 8' correspondingly arranged instead of the two sets of fingers or blades extending at angles to each other as shown in Figure 1.

It will be apparent that the improved method affords a simple, practical and expeditious means of producing a structure of the character described, and that, besides the facility and accuracy with which the curved and twisted contour of the blades or fingers is effected by the new process, the formation of such a twisted outline stiffens and strengthens the deflecting blades or fingers and enables them to withstand a greater force or pressure than baffle elements of bent form but lacking the twisted contour.

While I have illustrated and described what I now regard as the preferred mode of practicing the invention, I desire to reserve

the right to make all such changes or modifications as may fairly and properly fall within the scope of the appended claims.

What I claim is:

1. The method of constructing a sheet metal plate with twisted baffle blades or fingers which consists in forming a plurality of slits in the sheet metal and removing some of the metal at the closed end of each slit to form enlargements or expansions of the inner ends of said slits, and then twisting the metal between each pair of adjacent slits.

2. The method of constructing a sheet metal plate with twisted baffle blades or fingers which consists in cutting from a metal sheet a plurality of narrow strips of material beginning at the margin of the sheet and enlarged at the inner ends of said strips, and then twisting the blades or fingers formed by the removal of said strips of material.

3. The method of constructing a sheet metal plate with twisted baffle blades or fingers which consists in punching in a metal sheet a plurality of parallel slots extending from the margin of the sheet and terminating in openings at their inner ends of greater diameter than the width of said slots, and then twisting the fingers or blades formed by said series of slots.

In witness whereof I hereunto affix my signature.

LEWIS H. FALLEY.
